(57) **ABSTRACT**

A new pelargonium plant particularly distinguished by bright coral flower color; dark green leaf color; very weak leaf zonation; and medium vigor; is disclosed.

1 Drawing Sheet

1

Genus and species: *Pelargonium zonale (L.) L'Hér. ex Aiton.*

Variety denomination: **'KLEPZ23795'**.

BACKGROUND OF THE NEW PLANT

The present invention comprises a new and distinct variety of pelargonium, botanically known as *Pelargonium zonale (L.) L'Hér. ex Aiton* and hereinafter referred to by the variety name **'KLEPZ23795'**. **'KLEPZ23795'** originated from a controlled cross in August 2018 in Nairobi, Kenya between the commercial female pelargonium variety **'KLEPZ17484'** (U.S. Plant Pat. No. 30,335) and the proprietary male pelargonium variety **'PZ-2013-0119'** (unpatented).

Seeds from the controlled cross were obtained. The seeds were sown and plants were grown for evaluation. A single plant was selected in June 2019 and subsequently named **'KLEPZ23795'**. In July 2019 **'KLEPZ23795'** was first vegetatively propagated by vegetative stem cuttings in Stuttgart, Germany. **'KLEPZ23795'** was found to reproduce true to type in successive generations of asexual propagation via stem cuttings in Stuttgart, Germany.

SUMMARY

The following are the most outstanding and distinguishing characteristics of this new variety when grown under normal horticultural practices in Stuttgart, Germany.

1. Bright coral flower color;
2. Dark green leaf color;
3. Very weak leaf zonation; and
4. Medium vigor.

DESCRIPTION OF THE PHOTOGRAPH

This new pelargonium plant is illustrated by the accompanying photograph which shows an overall view of the plant in a pot. The photograph is of an approximately

2

20-week-old plant grown indoors in Stuttgart, Germany, in August 2022. The colors shown are as true as can be reasonably obtained by conventional photographic procedures.

DESCRIPTION OF THE NEW VARIETY

The following detailed descriptions set forth the distinctive characteristics of **'KLEPZ23795'**. Data was collected on 15-week-old plants in Stuttgart, Germany under greenhouse conditions in February 2024. Color references are to The R.H.S. Colour Chart of The Royal Horticultural Society of London (R.H.S.), 5th edition (2007).

Classification:

Family.—Geraniaceae.

Botanical.—*Pelargonium zonale (L.) L'Hér. ex Aiton.*

Common.—Pelargonium.

Designation.—**'KLEPZ23795'**.

Parentage:

Female parent.—**'KLEPZ17484'** (U.S. Plant Pat. No. 30,335).

Male parent.—PZ-2013-0119 (unpatented).

Plant:

Form.—Bushy.

Habit.—Upright.

Height (from top of soil).—30.0 cm.

Width (horizontal plant diameter).—31.0 cm.

Natural flowering season.—March to October.

Propagation type.—Vegetative by stem cuttings.

Time to produce a finished flowering plant.—12 weeks.

Time to initiate and develop roots.—4 weeks.

Root description.—Fine, dense, white, RHS 158A.

Flower type.—Zygomorphic.

Stems:

Quantity of stems per plant.—5-7.

Color.—RHS 143B.

Surface texture.—Pubescent.

Stem form.—Round.

<i>Diameter</i> .—0.7 cm.	5	<i>Sepals</i> :												
<i>Length</i> .—13.0 cm to 19.0 cm.		<i>Number per flower</i> .—5.
